(57) **CLAIM**

I claim the ornamental design for an invitation display, as shown and described.

DESCRIPTION

FIG. 1 is a perspective view of an invitation display, showing a first embodiment of the new design in a fully open configuration;

FIG. 2 is a front elevational view of FIG. 1;

FIG. 3 is a rear elevational view of FIG. 1;

FIG. 4 is a right-side elevational view of FIG. 1;

FIG. 5 is a left-side elevational view of FIG. 1;

FIG. 6 is a top plan view of FIG. 1;

FIG. 7 is a bottom plan view of FIG. 1;

FIG. 8 is a perspective view thereof, showing the first embodiment of the design in a closed configuration;

FIG. 9 is a front elevational view of FIG. 8;

FIG. 10 is a rear elevational view of FIG. 8;

FIG. 11 is a right-side elevational view of FIG. 8;

FIG. 12 is a left-side elevational view of FIG. 8;

FIG. 13 is a top plan view of FIG. 8; and

FIG. 14 is a bottom plan view of FIG. 8.

FIG. 15 is a perspective view of a second embodiment of the design in a fully open configuration;

FIG. 16 is a front elevational view of FIG. 15;

FIG. 17 is a rear elevational view of FIG. 15;

FIG. 18 is a right-side elevational view of FIG. 15;

FIG. 19 is a left-side elevational view of FIG. 15;

FIG. 20 is a top plan view of FIG. 15;

FIG. 21 is a bottom plan view of FIG. 15;

FIG. 22 is a perspective view of the second embodiment of the design in a closed configuration;

FIG. 23 is a front elevational view of FIG. 22;

FIG. 24 is a rear elevational view of FIG. 22;

FIG. 25 is a right-side elevational view of FIG. 22;

FIG. 26 is a left-side elevational view of FIG. 22;

FIG. 27 is a bottom plan view of FIG. 22; and,

FIG. 28 is a bottom plan view of FIG. 22.
